UNITED STATES PATENT OFFICE

ROBERT S. BOLGER, OF JAMAICA, NEW YORK, ASSIGNOR TO INTERNATIONAL MOTOR COMPANY, OF NEW YORK, N. Y., A CORPORATION OF DELAWARE

TRUSS-LADDER CONSTRUCTION

Application filed March 6, 1923. Serial No. 259,418.

This invention relates to ladder constructions, wherein the rungs are held in blocks secured by longitudinal truss sections. In ladders of this type made of wood it is found that the blocks of wood in which the rungs are mounted have a tendency to split and also that the rungs become loose and revolve when grasped.

This invention has for an object the provision of a construction of the above character wherein the rungs are secured against rotation between the truss members in a manner such that the means for securing the truss members together exerts a normal clamping action upon the rungs to secure them between suitable blocks on the trusses, and for another object, the provision of means whereby the blocks of wood are engaged in such manner that the usual tendency to split is considerably lessened. In order that these objects may be accomplished effectively, the ends of the rungs are flattened and formed sufficiently wide to separate the sections of the clamping blocks. When the securing bolts of the ladder are tightened, these parts have sufficient flexibility to clamp the rungs securely in place in spite of moderate changes in the thickness of the ends.

Other objects will appear as the description proceeds and reference will now be had to the accompanying drawings, wherein:

Figure 1 is a side elevation of a portion of the ladder.

Figure 2 is a front elevation of the ladder.

Figure 3 is a side elevation showing the manner of mounting the rungs in the blocks between the trusses.

Figure 4 is a vertical section taken along the line 4-4 of Figure 3, looking in the direction of the arrows.

Figure 5 is a view in section taken on line 5-5 of Figure 1 and looking in the direction of the arrows.

In the drawings, *a* and *b* represent the upper and lower longitudinal truss members respectively. *c¹* and *c²* represent companion blocks of wood or other suitable material, clamping the flattened ends *d'* of the rungs *d*. The usual blocks for mounting the rungs in existing ladder constructions are supplanted

by these companion block sections, each of the sections being formed with opposed faces *c³* and *c⁴* and recesses *c⁵* and *c⁶* which receive the flattened ends of the rungs *d*. Passing through the upper and lower truss members and companion blocks, and spaced upon either side of the ends of the rungs, are bolts *e* which secure the elements together and exert a clamping action upon the ends of the rungs.

In order that the rungs may be clamped securely in place, the thickness of the flattened ends *d'*, is made greater, in a plane transverse to that of the ladder, than the total depth of the two recesses, thus separating the opposed faces *c³* and *c⁴* of the blocks and causing the clamping action of the bolts to be exerted directly upon the flattened ends of the rungs through the blocks. The space between the blocks *c¹* and *c²* is made sufficiently great at the center to enable the blocks to contact at the outer edges of the faces.

It will be seen that if any tendency of the ends of the rungs to become loose appears, the parts will have sufficient elasticity to clamp the ends securely in spite of changes in size, thus not requiring continual tightening of the bolts. The bolts *e* may be tightened from time to time, as a safety precaution, and the parts maintained securely fastened together in this manner. It is impossible for the rungs to rotate since the means which secures the parts of the ladder as a unit serves also to clamp each individual rung in position. The flattened faces *d'* additionally serve to prevent any misalignment of the blocks *c¹* and *c²*.

At predetermined intervals rungs *d²* are provided, axial holes *h* being formed therein. Through-rods *g* extend through the holes and are threaded at each end to receive nuts *g¹*. The truss blocks *c¹* and *c²* are counter-bored the required depth, and the ends of the rungs are shortened to receive the nuts. The rods and the nuts as heretofore provided were located adjacent the lower side of the rung, thus forming a ladder, one end of which was preferably the ground end, whereas with the construction illustrated, either end may

be the ground end as both sides of the rungs present the same kind of tread.

On the under sides of the lower truss members *b*, metal tension members *f* are provided.

5 These are secured under the bolt heads *e* and serve to strengthen the ladder very materially.

The truss ladder construction described above has been found to be highly serviceable. It provides a structure in which every element is vital to the proper functioning of the others, and, as a result, the co-action between the component parts is complete. Various modifications in design and arrangement of parts may be made to suit the requirements of individual needs, and no limitation is to be imposed upon the invention, save as defined in the appended claims.

I claim as my invention:

20 1. A ladder construction of the character described comprising spaced truss members, rungs, companion blocks between the truss members, means to secure the rungs in the blocks, and means to secure the blocks between the truss members.

25 2. A ladder construction of the character described comprising spaced truss members, rungs, companion blocks between the truss members, means to secure the rungs between the blocks, and means to secure the blocks between the truss members.

30 3. A ladder construction of the character described comprising spaced truss members, rungs, companion blocks between the truss members, means to mount the rungs between the blocks, and means to clamp the rungs between the blocks.

35 4. A ladder construction of the character described comprising truss members, rungs having flattened surfaces at their ends, companion blocks between the truss members, means to mount the rungs between the blocks, and means to clamp the flattened ends of the rungs between the blocks.

40 5. A construction of the character described comprising truss members, rungs having flattened surfaces at their ends, companion blocks between the truss members, spaced recesses in the blocks to receive the ends of the rungs, the combined depth of the recesses being less than the thickness of the ends of the rungs, and means to secure the truss members and blocks together to clamp the rungs in position.

45 6. A ladder construction of the character described comprising upper and lower longitudinal truss members at either side of the ladder, means to secure rungs between the truss members, and metallic tension members secured to the lower truss members.

50 7. A ladder comprising side members, a plurality of rungs mounted between the side members, shoulders on the rungs to engage the side members to space the members properly, and means passing through certain of

the rungs to secure the side members against the shoulders, the lengths of the rungs between shoulders and adjacent ends being less than the thickness of the side members.

55 8. A ladder construction of the character described comprising spaced truss members, rungs, companion blocks between the truss members, said blocks being formed with depressions in which the rungs seat, the combined depth of the depressions being less than the corresponding dimensions of the rungs, means to secure the rungs in the depressions, and means to secure the blocks between the truss members.

60 This specification signed this 2nd day of so March, A. D. 1928.
